UNITED STATES PATENT OFFICE

ANTON FRANK BROTH, OF KOHLER, WISCONSIN, ASSIGNOR TO KOHLER COMPANY, OF KOHLER, WISCONSIN, A CORPORATION OF WISCONSIN

SWITCH BOX FOR AUTOMATIC GENERATING PLANTS

Original application filed October 5, 1925, Serial No. 60,702. Patent No. 1,734,557. Divided and this application filed May 23, 1927. Serial No. 193,658.

This invention relates to gas-engine-operated generating units of the demand starter type and has for its object to provide a switch box for containing the automatic switching mechanism so that it may be completely sealed to prevent tampering therewith and, when closed, constitutes a tight-fitting container providing the necessary ventilation to take care of such arcing as may occur, but inaccessible to insects that may interfere with the operation.

Another object of the invention is to provide such a switch box with a tight-fitting cover of such construction that, when opened, free access may be had to the switching mechanism for adjustment or repairs.

Another object of the invention is to provide such a cover for switch boxes that will not only enclose the switching mechanism mounted on the front of a switch panel but will cover and protect the wiring connections on the back of the panel.

Another object of the invention is to construct a switch box having great strength and rigidity, adapted to be bolted to the machine and affording proper support for a slate or other insulating instrument panel on which the switching mechanism is mounted.

Another object of the invention is to provide such a switch box with a hooded main knife switch for controlling the connection of the generating unit with the mains and so arranged that, when closed, it is tightly sealed and completely enclosed so that access may not be had thereto or to the fuses associated therewith without first opening the switch.

This application constitutes a division of my application for Automatic generating plants, Serial No. 60,702, filed October 5, 1925, which has become Patent No. 1,734,557, November 5, 1929.

With the above and other objects in view the invention consists in the switch box for automatic generating plants as herein claimed and all equivalents.

Referring to the accompanying drawings

in which like characters of reference indicate the same parts in different views,

Fig. 1 is a longitudinal sectional view of a switch box constructed in accordance with this invention, showing the open position of the knife switch in dotted lines;

Fig. 2 is a bottom view thereof with a portion of the bottom plate broken away showing the mounting flange on the end casting;

Fig. 3 is a transverse sectional view on the plane of line 3—3 of Fig. 1, showing the open position of the cover in dotted lines;

Fig. 4 is a plan view with the cover sectioned;

Fig. 5 is a front perspective with the knife switch open;

Fig. 6 is a rear view of the front end casting;

Fig. 7 is a detail view of the resetting rod;

Fig. 8 is a detail view of one of the resistors and the clip therefor;

Fig. 9 is an end view of the clip, and

Fig. 10 is a view of the clamping member thereof.

In these drawings, 10 indicates the front end casting and 11 the other, the two being connected by a bottom plate 12 and supporting between them a panel 13 of slate or other suitable insulating material. In detail each end casting has a deep mounting flange 100 integral with it at its lower edge and provided with mounting studs 101 for bolting the switch box to the machine. Insulated binding posts 102 for making heavy wiring connections with the generator and the battery form bolts passing through these mounting flanges and at the same time clamp the bottom plate 12 in place against the bottom of the mounting flanges to form the bottom of the switch box. The slate panel 13 bears at its lower edge upon the bottom plate 12 and also bears along its vertical edges against flanges 103 formed on the end castings and is rigidly clamped in place by screws 104 threading into ears 105, which project from these flanges near their upper ends. At its lower edge the slate is clamped to the bottom plate 12 by a bolt 106 passing through it and through an angle bracket 107.

With the above and other objects in view the invention consists in the switch box for automatic generating plants as herein claimed and all equivalents.

107 bolted to the bottom plate 12. In this manner the main frame structure of the switch box consisting of the end castings, the bottom plate and the insulating panel, to 5 produce the ends, the bottom and the back of the box, are rigidly clamped together to form a strong and substantial supporting structure on which the other parts are mounted.

10 A sheet metal cover 14 closes the front and top of the box and extends approximately half way down the back of the box, where it is spaced from the panel to guard and protect the wiring connections on the 15 back of the panel. At this rear end the cover is pivotally mounted by means of angle lugs 108 spot welded thereto and pivotally threaded on screws 109 passing through end casting 11 and through an outstanding lug 20 110 on end casting 10. These pivotal points are not in alignment for one lug 108 is on the inside of the cover and the other lug is on the outside of the cover for convenience in attaching the pivot screws and 25 sealing them, as will be later described, but the flexibility of the cover is such as to permit of this departure from conventional practice. The cover 14 is shaped to conform with the rounded corners of the box 30 and, when closed, bears at its edges against inwardly projecting stop flanges 111 formed on the end castings to make a tight fit therewith, such flanges being slightly offset from the edges of the end castings so that the 35 cover will be countersunk and will fit on a shouldered seat at its side edges. The slate panel 13 extends through the flanges 111 so as to contact with the cover and form a tight sealing closure therewith. The lower 40 front edge of the cover is bent to form a rearwardly extending flange 112 contacting with an upwardly bent flange 38 at the front edge of the bottom plate 12, this contact also forming a tight fitting closure.

45 The flange 38 of the bottom plate is recessed at its ends to take the mounting flanges 100 of the end castings and fit behind the stop flanges 111 to which they are secured by screws 114. Screws 115 pass 50 through the cover at its side edges near the lower edge and thread into the flanges 111 to lock the cover and, as it is desirable to seal the switch box to prevent tampering therewith or a change of adjustment except 55 at the factory or service stations, these screws, as well as the pivot screws 109, are adapted to be sealed in place by having a sealing wire passed through diametrical openings in their heads and through openings in convenient sealing lugs 116 and then secured with lead seals, making it impossible to remove the cover or obtain access to the switching mechanism without destroying the seals.

60 65 The end casting 10 has deep top and side

flanges forming a hood 117 for containing a knife switch 63 and fuses 17, the blades 15 of said knife switch being carried by a hinged cover 16 which is pivotally mounted between the side flanges of the hood and adapted, when closed, to fit within the hood walls, as shown in Fig. 1. In this manner the main switch is required to be opened in order to gain access to the fuses 17.

Mounted on the panel 13 within the switch 75 box are three magnetic switches 18, 19 and 20, respectively, the first of which is the control switch for starting and stopping the power plant in the presence or absence of a load, the second is the generator relay 80 for connecting the generator with the line when it functions, and the third is the cranking switch for cranking the engine with the generator operating as a motor.

A thermostatic switch 29 is provided for 85 automatically opening the cranking circuit after a period sufficient for cranking so as to prevent depletion of the battery when, for any reason, the engine cannot be cranked, as upon the absence of fuel, and this consists of a heating coil 30 secured to a strip of bi-metallic thermostat metal 31, which is mounted at one end on the insulating panel 13 and at the other end carries a contact 32 to engage a contact 32 carried by a lever 33 mounted on a pivot block 34 and held in either its closed or its open position by an arched spring 35 engaging said pivot block and a projection of the lever. This spring serves to hold the lever in either of 90 its positions by having its outer end carried from one side to the other of the line connecting its inner end and the pivotal axis of the lever. A resetting rod 36, serving as an indicator to show by its projecting 95 through an opening in the switch cover 14 that the thermostat switch is open, is pivotally mounted on the lever 33 and is guided by passing through an opening in a guide member 37 mounted on the upwardly extending front flange 38 of the bottom member 12. The cover 14 is depressed around the opening through which the resetting rod 36 projects so as to bear against the guide member 37 and make a tight sealing fit 100 therewith, thereby avoiding the necessity for making a tight fit between the rod and its opening in the cover.

Mounted on the rear of the insulating panel in suitable supporting clips 118 is a 105 battery-charging resistance element 39 and a field rheostat resistance element 40, both having adjustable tap clips 41 to permit of resistance variation. The resistance of the resistance element 39 between the tap clip 110 and one end thereof is adapted to be short circuited by a charge-varying switch 42, preferably of the push and pull type, mounted through an opening in the end casting 11.

A trouble lamp 43, preferably controlled 115

5 by a switch 44 and mounted on the hood of end casting 10, is connected across the generator terminals of the knife switch to constitute a test load for starting the unit in operation while disconnected from the mains for proving that the power plant is in operative condition and so eliminating it from consideration when trouble occurs on the line.

10 It will be noted that the enclosure for the switch mechanism has closely fitting parts that make it impossible for insects to gain admission and interfere with the operation of the switches. However, openings 45 may 15 be provided in the bottom plate for ventilation, but these are preferably covered with wire screen 46 to exclude insects.

What I claim as new and desire to secure by Letters Patent is:

20 1. A switch box comprising end castings, a horizontal bottom member connected thereto, a vertical insulating panel mounted between the end castings and fitting against the bottom member, a cover hinged to the 25 end castings and engaging the bottom member and forming a tight enclosure with the end castings and the panel and the bottom member, and switching mechanism mounted on the panel within the enclosure, there being 30 screened openings in the bottom member for ventilation and preventing the entrance of insects to the enclosure.

25 2. A switch box comprising end castings, a horizontal bottom member connected thereto, a vertical insulating panel mounted between the end castings and fitting against the bottom member, a cover hinged to the 35 end castings and engaging the bottom member and forming a tight enclosure with the end castings and the panel and the bottom member, and switching mechanism mounted on the panel within the enclosure.

30 3. A switch box comprising end castings provided with mounting flanges extending inwardly from their lower ends and having means for connection with a support, a horizontal bottom plate connecting the end castings, vertical flanges projecting from the end castings, a vertical insulating panel fitting against said flanges and secured thereto and bearing on the bottom plate, stop flanges on the end castings across the top and front thereof, and a cover hinged to the end castings and bearing on the stop flanges and 35 against the bottom plate to form a tight enclosure therewith.

35 4. A switch box comprising end castings, a horizontal bottom plate connecting the end castings, a vertical insulating panel also connecting the end castings and engaging the bottom plate, instruments mounted on the insulating panel with wiring connections on the back of the panel, and a cover pivotally mounted to the end castings back of the insulating panel and fitting between the end

40 castings over the top and the front of the switch box to form a tight fitting enclosure for the switch box and a protecting guard for the wiring connections back of the insulating panel when closed.

45 5. A switch box comprising end castings, a horizontal bottom plate connecting the end castings, a vertical insulating panel also connecting the end castings, pivot screws threaded in the end castings, a cover pivotally mounted thereon, screws securing the cover to the end castings, and means for sealing the screws against removal.

50 6. A switch box comprising end castings, a horizontal bottom plate connecting the end castings, a vertical insulating panel also connecting the end castings, shouldered flanges on the end castings along the top and front of the switch box, a cover hinged to the end castings and engaging said shouldered 55 flanges when closed, a flange bent up along the front edge of the bottom plate and fitting inside of and secured to the shouldered flanges of the end castings, and a flange on the edge of the cover bent back into engagement with the bottom plate.

55 7. A switch box comprising end castings, a horizontal bottom plate connecting the end castings, a vertical insulating panel also connecting the end castings, a cover hinged to the end castings and fitting between the end castings across the top and the front of the switch box, an upwardly extending flange on the bottom plate, a guide member secured thereto, and a switch-operating 60 push-rod passing through the guide member, the cover having an opening through which the end of the push-rod projects and being depressed around said opening to bear on the guide member, said cover forming a 65 tight-fitting enclosure with the end castings, the insulating panel, the bottom plate and said guide member.

65 8. A switch box, comprising opposite end walls having bottom mounting flanges directed toward each other, attaching means on the mounting flanges for supporting the switch box, a horizontal bottom wall connecting the end walls and secured to the mounting flanges, a vertical insulating panel 70 closely fitting between the end walls and against the bottom wall to constitute a fourth wall of the enclosure, said panel being spaced inwardly from the rear edges of the end walls, and a cover hinged to the 75 end walls at intermediate points of their rear edges and extending upwardly at a distance behind the panel and over the upper edge of the panel and bearing thereon to form the top wall of the enclosure and 80 downwardly into engagement with the bottom wall to form the front wall of the enclosure and having its side edges in tight fitting relation with the end walls.

9. A switch box, comprising opposite end

walls having bottom mounting flanges directed toward each other, attaching means on the mounting flanges for supporting the box, a horizontal bottom wall connecting the end walls and secured to the mounting flanges, a vertical insulating panel closely fitting between the end walls and spaced forwardly from the rear edges thereof and bearing against the bottom wall to constitute a fourth wall of the enclosure, switch mechanism mounted on the front of the panel, wiring on the back of the panel, and a cover hinged to the end walls at intermediate points of their rear edges and extending upwardly along the edges of the end walls to form a guard for the wiring and over the edge of the panel and bearing thereon to form the top wall of the enclosure and downwardly into engagement into the bottom wall to form the front wall of the enclosure and having its side edges in tight fitting relation with the end walls.

10. A switch box, comprising opposite end walls having bottom mounting flanges directed toward each other and having stop flanges and vertical flanges on their inner faces, attaching means on the mounting flanges for supporting the switch box, a horizontal bottom wall connecting the end walls and secured to the mounting flanges, a vertical insulating panel closely fitting between the end walls and mounted on the vertical flanges and bearing against the bottom wall to constitute a fourth wall of the enclosure, said panel being spaced inwardly from the rear edges of the end walls, and a cover hinged to the end walls at intermediate points of their rear edges and extending upwardly at a distance behind the panel and over the upper edge of the panel and bearing thereon and on the stop flanges to form the top wall of the enclosure and downwardly into engagement with the bottom wall and bearing on the stop flanges to form the front wall of the enclosure.

In testimony whereof, I affix my signature.

ANTON FRANK BROTHZ.
